CLAIM

The ornamental design for a window component as shown and described.

DESCRIPTION

1. Window component

FIG. 1.1 is an enlarged, front perspective of the window component,

FIG. 1.2 is an enlarged, rear perspective view of the window component shown in FIG. 1.1,

FIG. 1.3 is a top view of the window component shown in FIG. 1.1,

FIG. 1.4 is a bottom view of the window component shown in FIG. 1.1,

FIG. 1.5 is a right side view of the window component shown in FIG. 1.1, the left side being a mirror image thereof,
FIG. 1.6 is a front view of the window component shown in FIG. 1.1, and,

FIG. 1.7 is a rear view of the window component shown in FIG. 1.1.

The broken lines of FIGS. 1.1, 1.2, 1.6 and 1.7 illustrate structure that forms no portion part of the claimed design.
